UNITED STATES PATENT OFFICE.

WILLIAM ADAM FULFORD, OF ELKHORN, WEST VIRGINIA, ASSIGNOR OF ONE-HALF TO
WILLIAM E. WOOD, OF ELKHORN, WEST VIRGINIA.

TENSIONING DEVICE.

1,147,318.

Specification of Letters Patent.

Patented July 20, 1915.

Application filed December 8, 1914. Serial No. 876,058.

To all whom it may concern:

Be it known that I, WILLIAM ADAM FULFORD, a citizen of the United States of America, residing at Elkhorn, in the county 5 of McDowell and State of West Virginia, have invented certain new and useful Improvements in Tensioning Devices, of which the following is a specification.

This invention relates to tensioning devices and with regard to certain more specific features thereof to wire stretchers or the like adapted to be used in drawing the ends of a broken strand of wire together for the purpose of splicing them or for 15 drawing taut a slack wire while a portion of the wire is being removed and the ends joined.

It is, of course, to be understood that the mechanism hereinafter illustrated and described is capable of other uses and applications without material modification.

One of the objects of the present invention is to provide a simple and practical tensioning device of the above character having 25 few parts which will be inexpensive to manufacture and assemble.

A further object is to provide a device of the above character which will be reliable and efficient in use in operation.

30 A further object is to provide a device which may be easily and conveniently operated and adapted to evenly distribute the strains exerted thereon.

Other objects will be in part obvious from 35 the annexed drawings and in part indicated in connection therewith by the following analysis of this invention.

This invention accordingly consists in the features of construction, combination of 40 parts, and in the unique relations of the members and in the relative proportioning and disposition thereof; all as more completely outlined herein.

To enable others skilled in the art fully to 45 comprehend the underlying features thereof that they may embody the same by the numerous modifications in structure and relation contemplated by this invention, drawings depicting a preferred form have been annexed 50 as a part of this disclosure, and in such drawings, like characters of reference denote corresponding parts throughout all the views, of which:—

Figure 1 is a detail plan view of the complete device; Figs. 2 and 3 are views taken

at right angles to each other of one of the parts.

Referring now to the drawings in detail and more particularly to Fig. 1, 5 denotes a reversible ratchet centrally mounted upon 60 a threaded bar 6, the opposite ends of which are respectively right and left hand threaded. The bar 6 is supported in two bearing or guide plates 7 reinforced by a central brace or supporting plate 8. The opposite ends of 65 these members 7 support a guide bar 9 upon which slide two movable members 10, the opposite ends of which are provided with openings threaded to engage the right and left hand threads of the bar 6. These members 10 are preferably cylindrical and each is adapted to support a pair of cable eyes 11, Figs. 2 and 3, one at each side of the threaded bar. About these cable eyes is secured a flexible cable 12 having a loosely mounted 70 clevis 13 to which is secured a clamp 14, usually termed a "come along" block.

One or both ends of the threaded rod may be provided with a squared end 15 adapted to be engaged by a crank handle 16 in order 80 that the threaded bar may be rapidly rotated, as when assembling the parts prior to the stretching operation.

It is thought that the use and operation of a device of this character is clear from the 85 above disclosure. A brief statement, however, is substantially as follows: When, for example, it is desired to splice a broken wire, the ends of the wire are clamped in the "come along" blocks attached to each 90 clevis 14. The flexible wire cables 12 are then threaded through each clevis and secured about the cable eyes in the manner shown. These cable eyes are then mounted upon opposite sides of the threaded opening 95 on the members 10 and the crank rotated or the ratchet actuated to draw these blocks slightly together. When the parts are assembled, and the ends of the cable drawn together as far as possible by means of the 100 crank, the ratchet is actuated by means of the ratchet lever 17 to rotate the oppositely threaded rod and draw the members 10 toward each other along the guide rod 9. It is to be noted that the parts are so arranged 105 that the strain is exerted equally in opposite directions and in substantial alinement with the axis of the rod 6. The ratchet mechanism which is perhaps the most powerful form of power multiplying mech- 110

anism applicable from a commercial aspect to the present device, will easily and quickly draw the members 10 sufficiently close together to permit a splicing of the ends of 5 the wire. After this has been done, the ratchet mechanism may be released or reversely operated or the crank 16 operated to separate the parts and permit a removal of the "come along" blocks from the wire.

10 It is thus seen that the present invention provides a simple and practical device of the above general character adapted to accomplish, among, others, all of the objects and advantages above set forth.

15 Without further analysis, the foregoing will so fully reveal the gist of this invention that others can by applying current knowledge readily adapt it for various applications without omitting certain features 20 that, from the standpoint of the prior art, fairly constitute essential characteristics of the generic or specific aspects of this invention, and therefore such adaptations should and are intended to be comprehended within 25 in the meaning and range of equivalency of the following claims.

What I claim is:

1. In a wire stretcher, in combination, an oppositely threaded rod, a reversible ratchet 30 and lever mechanism associated therewith, guides at each side of said ratchet, a brace

connecting said guides, a guide bar passing through said guides parallel to said threaded rod, members threaded on said rod and supported by said bar, cable eyes at each side of said rod on each of said members, cables, each having its ends mounted on said eyes, and clamps connected with said cables adapted to exert a pull along the axis of said rod.

2. In a wire stretcher, in combination, an oppositely threaded rod, a reversible ratchet and lever mechanism associated therewith, guides at each side of said ratchet, a brace 45 connecting said guides, a guide bar passing through said guides parallel to said threaded rod, members threaded on said rod and supported by said bar, cable eyes at each side of said rod on each of said members, cables each having its ends mounted on said eyes, and clamps connected with said cables adapted to exert a pull along the axis of said rod, said rod having an angular end and a crank handle adapted to fit said end whereby said rod may be actuated independently 50 of said ratchet and lever mechanism.

In testimony whereof I affix my signature in presence of two witnesses.

WILLIAM ADAM FULFORD.
